(No Model.)

I. KLING.
CAR COUPLING.

No. 349,655.

Patented Sept. 21, 1886.

UNITED STATES PATENT OFFICE.

ISAAC KLING, OF LOUISVILLE, KENTUCKY.

CAR-COUPING.

SPECIFICATION forming part of Letters Patent No. 349,655, dated September 21, 1886.

Application filed July 27, 1886. Serial No. 209,236. (No model.)

To all whom it may concern:

Be it known that I, ISAAC KLING, of Louisville, in the county of Jefferson and State of Kentucky, have invented certain new and useful Improvements in Car-Couplers; and I do hereby declare that the following is a full, clear, and exact description thereof, reference being had to the accompanying drawings, and to the letters of reference marked thereon, which form part of this specification, in which—

Figure 1 is a vertical longitudinal section of the draw-bar of a car and coupling device complete. Figs. 2, 3, 4, 5, 6, 7, and 8 are details of the various parts of the coupler.

15 This invention relates to improvements in automatic car-couplers of the loose-pin-and-link variety; and it consists in the hereinafter-described construction and arrangement of parts pointed out in the appended claims, and 20 readily understood upon reference to the illustrations in the accompanying drawings, forming part of this specification.

25 Referring by letter to the drawings, A designates a hollow draw-bar of ordinary construction, having the flaring draw-head A'. The interior of the draw-head converges from its mouth to the outer end of the recess or hollow of the draw-bar, which recess is rectangular in cross-section, about two and one-half 30 or three inches in diameter, and extends nearly to the rear end of the draw-bar, as shown.

35 F is a bolt entering a proper opening in the inner end of the draw-bar, and retained in place by the tapered key E, that passes into proper slots in the draw-bar and said bolt. The said bolt is adapted to engage in a suitable opening in a front transverse iron bar on the car-truck, the key G passing through a 40 suitable opening in the bolt in rear of said iron bar, and aiding in securing the former to the latter.

45 C is a pin of ordinary construction, which passes into the openings W and H in the upper and lower surfaces, respectively, of the draw-bar, and retains the link B in place. y is the head of said pin, by which it may be lifted to release the link and uncouple the draw-bars.

50 R is a block of general rectangular shape, situated in the recess of the draw-bar near the inner end of the link. The outer end of said block is bifurcated, and is provided with a

downwardly-looking shoulder, X, between the arms of its bifurcation.

U is an oscillating or swing block pivoted by the pin T between the bifurcations of the block R. The block U is provided with the outwardly-extended upper corner, V, and on its inner edge with the upwardly-looking shoulder S. The parts are so constructed and arranged in relation to each other that when the shoulder S bears against the shoulder X the point V will be depressed and extended forward by gravity, so as to stand under the point of the pin C and prevent its descent. 65 When the link B, however, enters the draw-head, it impinges against the swinging block, drives the point V inward and upward, and allows the pin to descend and retain the link in the draw-head. 70

T is a concave part of the front edge of the block U, against which part the end of the link strikes, and is thereby prevented from sliding under the lower edge of said block and wedging it in the draw-bar. This concave part of 75 the front edge also serves to keep the link horizontal, so that its outer end will enter the opposite draw-head at right angles to the outer end thereof.

Q is a hook on the lower part of the inner end of the block R. The said hook looks upward and has a convex or rounded face at its point, and immediately above its shank, in the end of the block R, is a recess, q, for a purpose 80 hereinafter explained. 85

I is a long block of general rectangular shape bearing against the bottom of the recess of the draw-bar and deeply bifurcated at its outer end, so as to form the arms W', parallel and rectangular in cross-section. 90

i is a longitudinal groove in the upper surface of the body of the block I, and J is a key or wedge for insertion in said groove. The wedge J has on its under surface the wedge-shaped projections j j, which rest in corresponding recesses in the floor of the groove i, so that the wedge and block I can be inserted together in the recess or draw-bar. 95

j' is a transverse opening through the wedge, near the heel of the same. This opening is 100 for the purpose of drawing the wedge outward and unbinding the block I. To bind the said block in place a rod is inserted through the mouth of the draw-head and the wedge J is

driven inward, so that its projections *j* ride upward and inward on their recesses. To unbind the block *I* a hook-rod issimilarly inserted, its point engaged in the opening *j'* and the 5 wedge drawn outward. The block *I* can then be removed from the draw-bar, with the wedge resting upon it. The block *I* can be thus fixed in place in the recess of the draw-bar, the wedge binding against the roof of the recess.

10 *L* is a coil-spring, the inner end of which is secured to or in the body of the block *I* between the arms *W'*, its outer end bearing against the inner end of the shank of a hook, *N*, from which a pin, *M*, extends inward and 15 is surrounded by the coil-spring, so as to support the same. The point of the hook *N* looks downward, being adapted to engage with the hook *Q* on the block *R*. The two hooks do not bind on each other tightly, and when engaged the point of the hook *N* enters the recess *q*, to prevent it disengaging from the hook *Q*.

15 *P* is a longitudinal slot running from side to side through the body of the hook *N*, and 20 *O* is a transverse pin passing through said slot and having its ends secured to the arms *W'* of the block *I*. It is evident that when the link has struck and turned upward the block *U* the block *R* will be pressed inward, and 25 will press inward the hook *N* against the action of the spring *L*, so that no breakage, caused by jar, will take place in coupling. The pressing back of the block *R* also gives more clearance for the fall of the pin. Should 30 the hooks become accidentally uncoupled, the pressing back of the block *R* will cause the hook *N* to ride over and engage the hook *Q*, and the recess *q* will hold them engaged, as explained.

35 *K* is a disengaging-bar for the hook *N*. The said bar has its lower end pivoted to the shank of the hook *Q* in a recess in the side of said shank, and is provided with the inclined shoulder *k*, flush with the upper surface thereof, so that the point of the hook *N* rests partially on said shoulder. The upper end of the bar *K* rests against the inner end 40 of a groove, *p*, made in the upper surface of the arms of the block *R*.

45 *Z* is a disengaging-rod with a handle on its end outside of the draw-head, and its inner end resting against the bar *K*. When the rod is pushed inward, it turns said bar on its pivot, and by means of the shoulder *k* raises the hook 50 *N* from the hook *Q*. The block *I* and wedge *J* can then be removed, as described.

Having described my invention, I claim as new—

1. The combination, with the recessed draw-bar, the link entering the draw-head, and the pin, of the sliding bifurcated block in the recess of the draw-bar, provided with the downwardly-looking shoulder between the arms of its bifurcation, the swinging block pivoted be-

tween the arms of the sliding block, provided 65 with the upwardly-looking shoulder on its inner edge to engage the shoulder on the sliding block, and the extended front outer corner to fall forward and downward and support the end of the pin, so as to prevent the same from falling, and devices, substantially as described, 70 in the recess of the draw-bar, to bear against the sliding block and prevent breakage by jar in coupling.

2. The combination, with the recessed draw-bar 75 and the sliding block, situated in the recess thereof, and having on its inner end the upwardly-looking hook, of the long bifurcated block *I*, having a longitudinal recessed groove in its upper surface, the wedge lying 80 in said groove having the projections *j*, to fit in the recesses therein, and binding the block *I* in the recess of the draw-bar, the coiled spring secured to or in said block *I*, between the arms thereof, and the slotted downwardly-looking hook attached to the block *I*, between the arms thereof, by means of a pin passing through its slot and engaging the upwardly-looking hook on the sliding bifurcated block, 85 substantially as specified.

3. The combination, with the link and pin, 90 of the herein-described coupler-head, composed of the recessed draw-bar *A*, having the flaring draw-head *A'*, the bifurcated block *R*, provided with the shoulder *X*, hook *Q*, and recess *q*, the pivoted block *U*, provided with the shoulder *S* and point *V*, the bifurcated block *I*, provided with the recessed groove *i* and arms *W'*, the wedge *J*, having the projections *j* and opening *j'*, spring *L*, pin *O*, and hook *N*, provided with the slot *P*, and pin *M*, all constructed and arranged substantially as and for the purpose specified.

4. The combination, with the recessed draw-head, bifurcated block *I*, and hook *N*, connected thereto, of the sliding block *R*, hook *Q*, firmly secured thereto or forming part thereof, the disengaging-bar pivoted to the hook *Q*, and the disengaging-rod *Z*, moving in the groove *P* of the sliding block, substantially as specified.

5. The combination, in a car-coupler, of the downwardly-looking hook *N*, connected with a block, *I*, in the recess of the draw-head, near the bottom of the same, the upwardly-looking hook *Q*, provided in the side of its shank with the recess *q'*, the disengaging-bar *K*, having its lower end pivoted in the recess *q'*, and provided with the shoulder *k*, and the disengaging-rod *Z*, moving in the groove *p* of the block *R*, substantially as specified.

In testimony that I claim the foregoing as my own I affix my signature in presence of two witnesses.

ISAAC KLING.
